UNITED STATES PATENT OFFICE

1,996,777

CHILLING DEVICE

Henry E. von Seggern and Ernest A. von Seggern,
Escondido, Calif.

Application June 29, 1932, Serial No. 619,896

18 Claims. (Cl. 62—126)

Our invention relates to chilling devices, and the objects of our invention are:

First, to provide a device of this class which is particularly suited for cooling liquids, such as milk, which may be poured thereover;

Second, to provide a chilling device in which the surfaces thereof may be made smooth and flat so as to be readily cleaned, thereby providing a device which may be easily maintained in a sanitary and sterile condition;

Third, to provide a device of this class which is particularly efficient by reason of ample contact of the cooling medium and the substance to be cooled with the inner and outer surfaces of the device;

Fourth, to provide a device of this class in which the cooling medium may be readily, quickly and completely drained from the chilling device so as to permit sterilization;

Fifth, to provide a device of this class which incorporates a preliminary cooling means and a final cooling means or chilling means, the first of which may use water as a cooling medium, while the second utilizes a refrigerant so that the substance to be cooled may be progressively reduced in temperature as it flows over the chilling unit;

Sixth, to provide a device of this class in which the gas evolved from the refrigerant is permitted to flow upwardly and collect yet causing only a minimum amount of disturbance to the liquid, so that the gas may be collected in a relatively dry state without the use of extra equipment for this purpose;

Seventh, to provide a chilling device which incorporates a novel means of circulating the refrigerant therethrough and of separating the various components of the refrigerant for re-circulation, and

Eighth, to provide on the whole a novelly constructed chilling unit which is durable efficient in its action and which will not readily deteriorate or get out of order.

With these and other objects in view as will appear hereinafter, our invention consists of certain novel features of construction, combination and arrangement of parts and portions as will be hereinafter described in detail and particularly set forth in the appended claims, reference being had to the accompanying drawing and to the characters of reference thereon which form a part of this application, in which:

Figure 1 is a side elevational view of our chilling device with parts and portions broken away and in section to facilitate the illustration; Fig.

2 is an end elevational view of the trough member from which the substance to be chilled is poured; Fig. 3 is an enlarged sectional view of our novel chilling unit taken through 3—3 of Fig. 1; Fig. 4 is an enlarged sectional view of the separator used in conjunction with our chilling unit, and Fig. 5 is an enlarged fragmentary sectional view through 5—5 of Fig. 1 showing the manner of arranging the tubes containing the refrigerant.

Similar characters of reference refer to similar parts and portions throughout the several views of the drawing.

Bracket support 1, water outlet tube 2, water inlet tube 3, end member 4, side plates 5, baffle members 6, distributing trough 7, refrigerant discharge pipe 8, cover plates 9, refrigerant inlet pipe 10, evaporator tubes 11, covering 12, collector trough 13, separator casing 14, baffle 15, valve 16, float 17, drain plate 18, gas outlet tube 19, oil collector pan 20, and equalizer pipe 21, constitute the principal parts and portions of our novel chilling device.

The herein described chilling device is particularly adapted for use in conjunction with our copending application entitled Cooling apparatus, Serial No. 619,897, filed in the United States Patent Office June 29, 1932.

A bracket support 1 is provided which is adapted to be secured to a vertical surface. Near its upper extremity the bracket support 1 supports a water outlet tube 2 which extends laterally therefrom. Directly below the water outlet tube the bracket 1 supports a water inlet 3 which extends in parallel disposed relation with the water outlet tube. These two members are connected at their extremities to a vertically arranged end member or connecting member 4. The two tubes 2 and 3 are joined at their adjacent sides to vertically disposed side plates 5 which are arranged in parallel disposed relation with each other and separated a distance considerably less than the diameters of the inlet and outlet tubes thereby forming a vertically arranged flat panel with upper and lower rims formed by the tubes 2 and 3, an extended rim formed by the end member 4, and a supported rim formed by the bracket 1. The tubes 2 and 3 are provided with openings 2a and 3a, respectively, which communicate with the chamber, designated A, formed by the side plates 5. Within the chamber there is provided a series of baffle strips 6 extending between the side members so as to cause water to flow back and forth in order to progress from the lower inlet tube to the upper water outlet tube, as shown by the arrows in Fig. 1.

- A distributing trough 1 is mounted above the water outlet tube. This trough is substantially semi-cylindrical in cross section and is provided with a series of holes 7a along its bottom directly over the water outlet tube 2. The ends of the trough are closed and provided with projections 7b arranged in pairs so as to straddle lugs 1a and 4a extending upwardly from the bracket support 1 and the end member 4.
- Immediately below the water inlet pipe 3 and projecting laterally from the bracket 1 is a refrigerant discharge pipe 8 which is also supported at its extended end by the end member 4. The refrigerant discharge pipe 8 and the water inlet pipe 3 are preferably positioned in engagement with each other and their horizontal sides are bridged by cover plates 9, as shown best in Fig. 3, so as to provide flat vertical surfaces between the two pipes.
- At the lower end of the bracket there is provided a horizontally extending refrigerant inlet pipe 10 which is disposed directly below the pipes 2, 3 and 8, in parallel relation therewith. Likewise, the refrigerant inlet pipe 10 is joined to the end member 4. The space between the refrigerant inlet and discharge pipes is filled with a plurality of vertically disposed evaporator tubes 11 which are rectangular in cross section so when positioned against each other, form substantially smooth outer surfaces. The ends of the evaporator tubes 11 are joined to the refrigerant inlet and discharge pipes so as to provide a plurality of independent fluid conductors between these two members. The evaporator tubes are provided with covering 12 on their exposed surfaces which provides a smooth, easily cleaned surface. The evaporator tubes are therefore in effect a pair of parallel disposed walls, such as the walls 5, connected by vertical partitions at closely spaced intervals.
- The refrigerant inlet pipe 10 rests in a substantially semi-cylindrical collector trough 13 which is closed at its end adjacent the bracket 1 and is provided with a spout 13a at its extended end, as shown in Fig. 1. The connections between the several pipes 2, 3, 8 and 10, and the plates 6 as well as the tubes 11 and collector trough 13 are rounded or made as smooth as possible so as to eliminate all corners or crevices where bacteria might lodge and to otherwise provide a surface which may be readily and quickly cleaned and sterilized.
- The refrigerant discharge pipe projects through the bracket 1 and into the lower portion of a separator casing 14 near one end thereof. This end is separated from the remaining portion of the casing by a baffle 15 which provides an opening 15a at the upper portion of the casing and an opening 15b at the lower portion of the casing. The extended end of the casing is provided with a liquid inlet 14a controlled by a valve 16 which is operated by a float 17 disposed between the extended end of the casing and the baffle 15.
- The upper margin of the baffle 15 which forms the lower edge of the opening 15a is joined to a drain plate 18 which is disposed at a slight angle and slopes towards the extended end of the casing 14. The drain is connected along its side margins to the casing so that liquid must flow down to the lower end of the drain plate. At this end the drain plate is provided with a low wall 18a and a rudimentary spout 18b. Liquid dripping from the drain plate 18 falls into a small oil collector pan 20 which is supported from the down turned end 19a of a gas outlet tube 19 projecting into the casing 14 from the extended end thereof.
- The refrigerant outlet pipe 8 is provided with a partition 8a at its end projecting into the casing 14, said partition covers the upper half of the refrigerant discharge pipe so as to form a gas collecting chamber disposed above the evaporator tubes 11.
- An equalizer pipe 21 communicates with the bottom of the separator casing between the baffle 15 and the end of the casing provided with the refrigerant discharge pipe 8. The equalizer pipe extends downwardly and joins the refrigerant inlet pipe 10 and continues to a storage chamber S, shown fragmentarily in Fig. 1. With this arrangement the evaporator tubes and separator casing may be filled with liquid refrigerant either from the storage chamber S or through the inlet opening 14a.
- Operation of our chilling device is as follows: The substance to be chilled, such as milk, is poured into the trough 1, whereupon it flows over the water outlet tube 2 and around the sides thereof onto the side plates 5, between which cooling water is circulated. The milk in the form of two sheets, one on each side of the chilling device, then flows over the water inlet pipe 3, across the cover plates 9 and over the refrigerant discharge pipe 8, and down the covering 12 provided over the evaporator tubes 11, so as to collect in the trough 13 where it may flow out the spout 13a into any suitable receptacle.
- The refrigerant is maintained at a level somewhat above the refrigerant discharge pipe 8, as shown in Figs. 1 and 4. The evaporated refrigerant in gaseous form is trapped in the pocket or chamber formed at the upper side of the refrigerant discharge pipe and flows out underneath the partition 8a, whereupon the gas bubbles up through the liquid refrigerant, passes through the opening 15a, flows over the drain plate 18, and is drawn into the gas outlet tube 19 which is connected to the intake side of a compressor, not shown. It is customary in some types of compressors, such as sulphur dioxide compressors, to provide a quantity of oil or other lubricant in the refrigerant. This oil collects on top of the liquid refrigerant between the baffle 15 and the end of the casing having the refrigerant discharge pipe 8. The bubbles of gas which pass up through the liquid refrigerant become coated with oil as they pass through the oil film on top and carry the oil over the baffle 15 on to the drain plate 18, whereupon the oil is deposited on the drain plate and flows into the oil collecting pan 20. The oil accumulates here until the gas outlet tube 19 is nearly submerged therein, whereupon the oil is drawn into the gas outlet tube with the gas. This arrangement ensures circulation of the lubricant with the gas but renders it practically impossible for liquid refrigerant to find its way into the gas outlet tube.
- By reason of the vertical arrangement of the evaporator tubes 11 these tubes may be quickly drained of the refrigerant for the purpose of sterilizing the chilling device. The gas particles which are evolved from the liquid refrigerant are free to flow through the refrigerant outlet pipe without undue agitation of the liquid refrigerant, whereby the gas maintains a relatively dry condition. Inasmuch as the float valve in the separator casing tends to maintain the refrigerant liquid level above the refrigerant discharge pipe 8, the evaporator tubes are normally full of liquid refrigerant. With the evaporator tubes 11

filled with liquid refrigerant the capacity of a compressor to remove heat from the evaporator tubes is practically directly proportional to the absolute suction pressure produced by the compressor, thus providing a particularly efficient evaporator construction.

Though we have shown and described a particular construction, combination and arrangement of parts and portions, we do not wish to be limited to this particular construction, combination and arrangement, but desire to include in the scope of our invention the construction, combination and arrangement substantially as set forth in the appended claims.

Having thus described our invention, what we claim as new and desire to secure by Letters Patent is:

1. In a chilling device, a hollow flat surfaced vertically disposed panel, a liquid refrigerant supply tube traversing the lower end thereof, a refrigerant discharge tube traversing the upper end thereof, a plurality of vertically disposed partitions arranged in spaced parallel disposed relation across and within said panel, said partitions forming evaporating spaces therebetween communicating with said supply tube and said outlet tube, whereby the gaseous particles of evaporated refrigerant are free to rise directly into said outlet tube, and a second hollow flat surfaced vertically disposed panel arranged directly above and joined at its lower margin to said first panel, a water inlet connected with the lower portion of said second panel, a water outlet connected with the upper portion thereof, and baffles disposed within said panel between said inlet and outlet for facilitating the circulation of water within said panel.

2. In a chilling device, a smooth flat surfaced hollow vertically disposed panel, enlargements protruding laterally from the surfaces of said panel but merging therein, said enlargements disposed at the upper and lower ends of said panel and across the central portion thereof, a water circulating means formed within said panel between the central portion and upper end thereof, and a refrigerant circulating means formed within said panel between said central portion and the lower end thereof.

3. In a chilling device, a smooth flat surfaced hollow vertically disposed panel, enlargements protruding laterally from the surfaces of said panel but merging therein, said enlargements disposed at the upper and lower ends of said panel and across the central portion thereof, a water circulating means formed within said panel between the central portion and upper end thereof, a refrigerant circulating means formed within said panel between said central portion and the lower end thereof, said refrigerant circulating means comprising an inlet pipe incorporated in the lower enlargement, an outlet pipe incorporated in the central enlargement, and vertically disposed evaporator tubes forming a plurality of independent conduits between said inlet and outlet pipes.

4. In a chilling device, a pair of thin hollow vertically disposed panels one arranged directly below the other and forming an upper and a lower panel, transversely extending enlargements at the adjacent ends and remote ends of said panels, said enlargements merging into the surfaces of said panels, a water circulating means associated with the upper panel, said lower panel comprising a plurality of vertically disposed rectangular evaporator tubes secured together side

by side so that their exposed sides form the surfaces of said lower panel, and an inlet pipe and an outlet pipe common to said tubes and incorporated in the enlargements bordering said lower panel.

5. In a chilling device, a smooth flat surfaced hollow vertically disposed panel, enlargements protruding laterally from the surfaces of said panel but merging therein, said enlargements disposed at the upper and lower ends of said panel and across the central portion thereof, a water circulating means formed within said panel between the central portion and upper end thereof, a refrigerant circulating means formed within said panel between said central portion and the lower end thereof, means for distributing a liquid along the upper enlargement whereby the liquid is caused to flow in sheets or films over the surfaces of said panel, and means for collecting said liquid at the bottom of said panel.

6. In a chilling device, a smooth flat surfaced hollow vertically disposed panel, enlargements protruding laterally from the surfaces of said panel but merging therein, said enlargements disposed at the upper and lower ends of said panel and across the central portion thereof, a water circulating means formed within said panel between the central portion and upper end thereof, a refrigerant circulating means formed within said panel between said central portion and the lower end thereof, said refrigerant circulating means comprising an inlet pipe incorporated in the lower enlargement, an outlet pipe incorporated in the central enlargement, vertically disposed evaporator tubes forming a plurality of independent conduits between said inlet and outlet pipes, means for distributing a liquid along the upper enlargement whereby the liquid is caused to flow in sheets or films over the surfaces of said panel, and means for collecting said liquid at the bottom of said panel.

7. In a chilling device, a pair of thin hollow vertically disposed panels one arranged directly below the other and forming an upper and a lower panel, transversely extending enlargements at the adjacent ends and remote ends of said panels, said enlargements merging into the surfaces of said panels, a water circulating means associated with the upper panel, said lower panel comprising a plurality of vertically disposed rectangular evaporator tubes secured together side by side so that their exposed sides form the surfaces of said lower panel, an inlet pipe and an outlet pipe common to said tubes and incorporated in the enlargements bordering said lower panel, means for distributing a liquid along the upper enlargement whereby the liquid is caused to flow in sheets or films over the surfaces of said panels, and means disposed at the lower edge of the bottom panel for collecting said liquid.

8. In a chilling device, a plurality of vertically disposed rectangular evaporator tubes secured together side by side so that their exposed sides form flat parallel disposed surfaces, an inlet pipe common to the one ends of said tubes, an outlet pipe common to the other ends of said tubes, said outlet pipe provided with a gas receiving pocket therein extending over said evaporator tubes, a separator chamber connected with said outlet, and means therein tending to maintain liquid refrigerant at levels above said outlet pipe whereby said evaporator tubes are normally completely filled and said outlet tube is only partially filled with liquid refrigerant.

9. In a chilling device, a pair of thin hollow

- vertically disposed panels one arranged directly below the other and forming an upper and a lower panel, transversely extending enlargements at the adjacent ends and remote ends of said panels, said enlargements merging into the surfaces of said panels, a water circulating means associated with the upper panel, said lower panel comprising a plurality of vertically disposed rectangular evaporator tubes secured together side by side so that their exposed sides form the surfaces of said lower panel, an inlet pipe and an outlet pipe common to said tubes and incorporated in the enlargements bordering said lower panel, said outlet pipe provided with a gas receiving pocket therein extending over said evaporator tubes, a separator chamber connected with said outlet, and means therein tending to maintain liquid refrigerant at levels above said outlet pipe whereby said evaporator tubes are normally completely filled with liquid refrigerant.
10. In a chilling device, a plurality of vertically disposed rectangular evaporator tubes secured together side by side so that their exposed sides form flat parallel disposed surfaces, an inlet pipe common to the lower ends of said tubes, an outlet pipe common to the upper ends of said tubes, said outlet pipe provided with its outlet opening disposed downwardly from its upper side thereby forming a gaseous refrigerant receiving chamber above said evaporator tubes.
15. In a chilling device, a plurality of vertically disposed evaporator tubes, a lower horizontal connecting pipe common to the lower ends of said tubes, an upper horizontal connecting pipe common to the upper ends of said tubes, the upper connecting pipe including an outlet aperture disposed below its upper side, said pipe forming along its upper portion above said outlet aperture an evaporated or gaseous refrigerant receiving chamber, a receptacle in communication with a source of refrigerant and connected with both said upper connecting pipe and said lower connecting pipe, said receptacle extending above the upper connecting pipe, and means for maintaining the liquid level in said receptacle above the upper connecting pipe whereby the gaseous refrigerant in said receiving chamber is caused to pass upwardly through additional liquid refrigerant.
20. In a chilling device, a plurality of vertically disposed evaporator tubes, a lower horizontal connecting pipe common to the lower ends of said tubes, an upper horizontal connecting pipe common to the upper ends of said tubes, the upper connecting pipe including an outlet aperture disposed below its upper side, said pipe forming along its upper portion above said outlet aperture an evaporated or gaseous refrigerant receiving chamber, an equalizer conduit connected to both the upper and lower pipes, a float chamber at the upper end of said conduit and receiving the outlet end of said upper pipe, and means in the float chamber for maintaining the liquid refrigerant level above the upper connecting pipe whereby the gaseous refrigerant in the receiving chamber is caused to pass upwardly through additional liquid refrigerant upon entering the float chamber.
25. In a chilling device, a plurality of vertically disposed tubes, a lower horizontal connecting pipe common to the lower ends of said tubes, an upper horizontal connecting pipe common to the upper ends of said tubes, the upper connecting pipe including an outlet aperture disposed below its upper side, said pipe forming along its upper portion above said outlet aperture an evaporated or gaseous refrigerant receiving chamber, a lubricant contained in the receiving chamber, whereby a lubricant contained in the refrigerant tends to rise and float on the surface of the liquid defining the receiving chamber, means connected with the outlet end of the upper connecting pipe arranged to maintain liquid refrigerant above the level in said upper pipe whereby the lubricant and gaseous refrigerant are caused to mix as they issue from said upper pipe and pass upwardly from the liquid surface in said means in the form of bubbles.
30. In a chilling device, an evaporator means in communication with a source of liquid refrigerant, said evaporator means having a gaseous refrigerant receiving chamber at its upper side, and a gaseous refrigerant outlet therefor below said upper side, a receptacle communicating with said outlet to receive gaseous refrigerant therefrom, and means for maintaining a liquid refrigerant in said receptacle at a level above said outlet whereby the gaseous refrigerant from the evaporator means is caused to pass through additional liquid refrigerant.
35. In a chilling device employing a refrigerant containing a lubricant, an evaporator means in communication with a source of liquid refrigerant, said evaporator means having a gaseous refrigerant receiving chamber at its upper side, and a gaseous refrigerant outlet therefor below said upper side, whereby a lubricant contained in the refrigerant tends to rise and float on the surface of the liquid refrigerant in said chamber and flow with the gaseous refrigerant through said outlet, a receptacle communicating with said outlet to receive gaseous refrigerant therefrom, and means for maintaining a liquid refrigerant in said receptacle at a level above said outlet whereby the lubricant issuing from the outlet tends to collect on the surface of the liquid refrigerant and the gaseous refrigerant is caused to pass upwardly through the lubricant and carry the lubricant therewith.
40. In a chilling device employing a refrigerant containing a lubricant, an evaporator means in communication with a source of liquid refrigerant, said evaporator means having a gaseous refrigerant receiving chamber at its upper side, and a gaseous refrigerant outlet therefor below said upper side, whereby a lubricant contained in the refrigerant tends to rise and float on the surface of the liquid refrigerant in said chamber and flow with the gaseous refrigerant through said outlet, a receptacle communicating with said outlet to receive gaseous refrigerant therefrom, means for maintaining a liquid refrigerant in said receptacle at a level above said outlet whereby the lubricant issuing from the outlet tends to collect on the surface of the liquid refrigerant and the gaseous refrigerant is caused to pass upwardly through the lubricant and carry the lubricant therewith.
45. In a chilling device employing a refrigerant containing a lubricant, an evaporator means in communication with a source of liquid refrigerant, said evaporator means having a gaseous refrigerant receiving chamber at its upper side, and a gaseous refrigerant outlet therefor below said upper side, whereby a lubricant contained in the refrigerant tends to rise and float on the surface of the liquid refrigerant in said chamber and flow with the gaseous refrigerant through said outlet, a receptacle communicating with said outlet to receive gaseous refrigerant therefrom, means for maintaining a liquid refrigerant in said receptacle at a level above said outlet whereby the lubricant issuing from the outlet tends to collect on the surface of the liquid refrigerant and the gaseous refrigerant is caused to pass upwardly through the lubricant and carry the lubricant therewith, and a collector means for the gaseous refrigerant and lubricant carried thereby.
50. In a chilling apparatus employing a refrigerant containing a lubricant, an evaporator means, a separator chamber and a float chamber communicating with the upper side of the evaporator means, a liquid refrigerant inlet in the float chamber, a float controlled valve therefor, said chambers being relatively disposed so that the float controlled valve maintains the liquid levels in both chambers above the evaporator means, a lubricant collecting means communicating with said separator chamber, a gaseous refrigerant outlet tube in proximity to the lubricant collecting means.
55. In a chilling device, a plurality of vertically disposed tubes, a lower horizontal connecting pipe common to the lower ends of said tubes, an upper horizontal connecting pipe common to the upper ends of said tubes, the upper connecting pipe including an outlet aperture disposed below its upper side, said pipe forming along its upper portion above said outlet aperture an evaporated or gaseous refrigerant receiving chamber, a lubricant contained in the receiving chamber, whereby a lubricant contained in the refrigerant tends to rise and float on the surface of the liquid defining the receiving chamber, means connected with the outlet end of the upper connecting pipe arranged to maintain liquid refrigerant above the level in said upper pipe whereby the lubricant and gaseous refrigerant are caused to mix as they issue from said upper pipe and pass upwardly from the liquid surface in said means in the form of bubbles.
60. In a chilling device, an evaporator means in communication with a source of liquid refrigerant, said evaporator means having a gaseous refrigerant receiving chamber at its upper side, and a gaseous refrigerant outlet therefor below said upper side, a receptacle communicating with said outlet to receive gaseous refrigerant therefrom, and means for maintaining a liquid refrigerant in said receptacle at a level above said outlet whereby the gaseous refrigerant from the evaporator means is caused to pass through additional liquid refrigerant.
65. In a chilling device employing a refrigerant containing a lubricant, an evaporator means in communication with a source of liquid refrigerant, said evaporator means having a gaseous refrigerant receiving chamber at its upper side, and a gaseous refrigerant outlet therefor below said upper side, whereby a lubricant contained in the refrigerant tends to rise and float on the surface of the liquid refrigerant in said chamber and flow with the gaseous refrigerant through said outlet, a receptacle communicating with said outlet to receive gaseous refrigerant therefrom, means for maintaining a liquid refrigerant in said receptacle at a level above said outlet whereby the lubricant issuing from the outlet tends to collect on the surface of the liquid refrigerant and the gaseous refrigerant is caused to pass upwardly through the lubricant and carry the lubricant therewith.
70. In a chilling device, a plurality of vertically disposed tubes, a lower horizontal connecting pipe common to the lower ends of said tubes, an upper horizontal connecting pipe common to the upper ends of said tubes, the upper connecting pipe including an outlet aperture disposed below its upper side, said pipe forming along its upper portion above said outlet aperture an evaporated or gaseous refrigerant receiving chamber, a lubricant contained in the receiving chamber, whereby a lubricant contained in the refrigerant tends to rise and float on the surface of the liquid defining the receiving chamber, means connected with the outlet end of the upper connecting pipe arranged to maintain liquid refrigerant above the level in said upper pipe whereby the lubricant and gaseous refrigerant are caused to mix as they issue from said upper pipe and pass upwardly from the liquid surface in said means in the form of bubbles.
75. In a chilling device, a plurality of vertically disposed tubes, a lower horizontal connecting pipe common to the lower ends of said tubes, an upper horizontal connecting pipe common to the upper ends of said tubes, the upper connecting pipe including an outlet aperture disposed below its upper side, said pipe forming along its upper portion above said outlet aperture an evaporated or gaseous refrigerant receiving chamber, a lubricant contained in the receiving chamber, whereby a lubricant contained in the refrigerant tends to rise and float on the surface of the liquid defining the receiving chamber, means connected with the outlet end of the upper connecting pipe arranged to maintain liquid refrigerant above the level in said upper pipe whereby the lubricant and gaseous refrigerant are caused to mix as they issue from said upper pipe and pass upwardly from the liquid surface in said means in the form of bubbles.

cant collecting means whereby lubricant may be drawn with the gaseous refrigerant into said tube.

18. In a chilling apparatus employing a refrigerant containing a lubricant, an evaporator means, a separator casing arranged opposite the upper portion of said evaporator means, a baffle dividing said separator casing into a pair of chambers communicating at their upper and lower portions, one of said chambers communicating with said evaporator means, a liquid refrigerant inlet in the other of said chambers, a

float controlled valve therefor tending to maintain the liquid refrigerant level above said evaporator means, an oil collecting means at the upper portion of said other chamber and communicating with said first chamber, and an evaporated or gaseous refrigerant outlet tube extending in contiguous relation to said oil collecting means whereby oil may be drawn into said tube with the gaseous refrigerant.
